DESIGN FOR A TEXTILE FABRIC OR SIMILAR ARTICLE

William H. Mayer, Jr., New York, N. Y., assignor to Commonwealth Textile Corp., a corporation of New York

Application July 3, 1936, Serial No. 63,645

Term of patent 3½ years

To all whom it may concern:

Be it known that I, William H. Mayer, Jr., a citizen of the United States of America and resident of the city of New York, county of New York, and State of New York, have invented a new, original, and ornamental Design for a Textile Fabric or Similar Article, of which the following is a specification, reference being had to the accompanying drawing, forming a part thereof.

The figure is a plan view of a piece of textile fabric or similar article showing my design, the unit of which is contained in dot and dash lines, which unit is repeated over the surface of the fabric in the relation indicated beyond the unit boundaries.

I claim:

The ornamental design for a textile fabric or similar article, as shown and described.
